EMILE GABRIEL ROYER, OF PARIS, FRANCE, ASSIGNOR TO SOCIÉTÉ ANONYME
"ORIONA," OF BRUSSELS, BELGIUM.

ELECTRIC INCANDESCENT LAMP.

1,063,496.

Specification of Letters Patent. Patented June 3, 1913.

Original application filed February 4, 1911, Serial No. 606,605. Divided and this application filed September 19, 1912. Serial No. 721,234.

To all whom it may concern:

Be it known that I, EMILE GABRIEL ROYER, a citizen of the French Republic, and resident of Paris, France, have invented certain new and useful Improvements in Electric Incandescent Lamps, of which the following is a specification.

The present invention which is a division of my application No. 606,605 filed Febr. 4th, 1911, relates to an electric lamp the novelty of which consists in that, on the end of an extension of the usual holder, the filaments are arranged in alternate positions in two horizontal planes or layers which are at different levels in such a manner that, in vertical projection, each filament of the upper plane of filaments is arranged substantially between every two filaments of the lower plane of filaments, or said upper filament crosses the lower filaments more or less at a right angle.

The accompanying drawing shows an example of the object of the invention.

Figure 1 is a view of one constructive form of the invention. Fig. 2 is a corresponding top view.

The filaments are arranged in two superposed horizontal planes or layers, the filaments of each of said planes alternating with respect to each other, in such a manner that, in vertical projection, each filament of the upper plane is located between every two filaments of the lower one. This arrangement of the filaments enables to furnish a maximum lighting in vertical direction, as well as sidewise.

The glass rod 1 supports a glass ring 2 on the outer portion of which are secured hooks

3 which hold the filament portions 4 of the lower plate, while the inner portion of the ring 2 is provided with hooks 5 which are intended to hold the filament portions 6 of the upper plane.

The form of arrangement of the filaments may differ, it may be round, oval, square or the like. More than two layers of filaments may be provided, according to the desired increasing of the intensity of the light emitted by the outer edge of said layers. The filament portions could also surround an axis, when providing a corresponding holding arrangement, thus forming a lighting globe.

Having now fully described my said invention, what I claim and desire to secure by Letters Patent, is:

An electric incandescent lamp comprising a bulb, a cap onto said bulb, a filament holder secured by one of its ends onto said cap, an extension of the opposite end of said holder, two sets of hooks of different lengths fixed onto said extension and a filament on each of said sets of hooks, both said filaments being secured in alternate positions in two horizontal planes or layers at different levels in such a manner that in vertical projection each filament portion of the upper plane of filaments is arranged substantially between every two filament portions of the lower plane of filaments.

In testimony whereof I have hereunto set my hand in presence of two witnesses.

EMILE GABRIEL ROYER.
